INVENTOR.
Nic Krump,
BY
Charles Turner Brown,
ATTORNEY.

UNITED STATES PATENT OFFICE.

NIC KRUMP, OF CHICAGO, ILLINOIS.

BENDING BRAKE.

Application filed December 12, 1921. Serial No. 521,750.

To all whom it may concern:

Be it known that I, NIC KRUMP, a citizen of the United States, and a resident of Chicago, in the county of Cook and State of Illinois, have invented certain new and useful Improvements in Bending Brakes, of which the following, reference being had to the drawing accompanying and forming a part hereof, is a specification.

10 This invention relates to bending brakes designed to be used in bending sheet metal of considerable thickness.

Among the objects of this invention are to obtain a bending leaf of great rigidity, 15 of economical construction, and not liable to break or get out of order, and by means of which a straight bend may be obtained.

In the drawing referred to Fig. 1 is a front elevation of a bending brake provided 20 with a bending leaf embodying this invention, and Fig. 2 is a vertical section on line 2—2 of Fig. 1, viewed as indicated by arrows.

A reference character applied to designate 25 a given part indicates said part throughout the several figures of the drawing wherever the same appears.

A represents the upper jaw of the brake, and is illustrated in Fig. 2 as comprising 30 members a, a', joined by bolts B, B, and provided with the lower, and bending, edge a''. C represents the lower jaw of the brake, and between jaws A and C sheet metal, as X, Fig. 2, is rigidly held as the same is bent 35 by the turning of the bending leaf E clockwise. F, F, are the pivots or fulcrums on which leaf E turns in the operation of the brake. f, f, Fig. 1, represent weighted levers by means of which the bending leaf is turn- 40 able on fulcrums F, F, to approach the upper jaw A.

In the operation of this bending brake a sheet of metal (X, Fig. 2), being placed between the upper jaw A and the lower jaw C, and held rigidly in position by the clamping of said upper jaw down thereonto, and the bending leaf E being turned clockwise on fulcrums F, F, the upper edge, (e) of said bending leaf is forced against the under side of said metal (X), bending said 50 sheet of metal around the edge a'' of said upper jaw. To prevent said upper edge, e, of said bending leaf E being forced from a straight line, by the bending of said leaf either laterally or longitudinally, I have 55 devised and used the constructions illustrated in Fig. 2.

In the construction illustrated in Fig. 2, the angle irons G, G, are attached to the bending leaf E by bolts g, g, and the U-shaped iron H is secured to said angle irons by bolts h, h.

I find, when the bending leaf is reinforced in the way illustrated and described, the upper edge thereof, when forced against 65 a sheet of metal held between the jaws of the brake, will remain straight, that is, will not be deflected in any way.

I claim:

In a bending brake provided with an upper and a lower jaw, the combination therewith of a bending leaf fulcrumed to turn around the lower edge of said upper jaw, said bending leaf comprising a sheet metal plate, angle irons rigidly attached to 75 the rear side of said plate, and an additional angle iron rigidly attached to said first named angle irons.

NIC KRUMP.
